DESIGN FOR A LATHER MIXER

Melvin Rolstad and Harry E. Cullen, Minneapolis, Minn., assignors to Rolstad Manufacturing Company, Minneapolis, Minn., a partnership composed of Melvin Rolstad, Lydia Rolstad, and Central Machine Works Company

Application December 9, 1940, Serial No. 97,174

Term of patent 14 years

To all whom it may concern:

Be it known that we, Melvin Rolstad and Harry E. Cullen, citizens of the United States, residing at Minneapolis, in the county of Hennepin and State of Minnesota, have invented a new, original, and ornamental Design for a Lather Mixer, of which the following is a specification, reference being had to the accompanying drawing, forming part thereof, and in which

Figure 1 is a side elevational view of a lather mixer, showing our new design;

Figure 2 is a top plan view of Figure 1; and Figure 3 is an end elevational view of Figure 1.

We claim:

The ornamental design for a lather mixer, substantially as shown.

MELVIN ROLSTAD.
